Attorney S.

UNITED STATES PATENT OFFICE.

PHILIP SCHNEIDER, OF CHICAGO, ILLINOIS.

RADIATOR.

1,356,562.

specification of Letters Patent. Patented Oct. 26, 1920.

Application filed March 1, 1919. Serial No. 280,066.

To all whom it may concern:

Be it known that I, PHILIP SCHNEIDER, a citizen of the United States, residing at Chicago, in the county of Cook and State 5 of Illinois, have invented new and useful Improvements in Radiators, of which the following is a specification.

This invention relates to radiators employed in connection with steam and hot 10 water heating systems, and its object is to provide a radiator having a novel and improved supply connection for the heating medium whereby the radiator will be more rapidly heated when the heating medium is 15 turned on.

In order that the invention may be better understood, reference is had to the accompanying drawing forming a part of this specification, and in said drawing,

20 An elevation of the invention, partly in section, is shown.

Referring specifically to the drawings, 5 denotes a radiator composed of a series of vertical sections 6 which are held assembled side by side in the customary manner. 25 Ordinarily, the radiator sections are inter-communicating at the top and the bottom only and the supply connection for the heating medium is made at the bottom. In the 30 present structure, the radiator sections also have a cross passageway 7 about midway be-

tween the top and bottom, and a supply connection 8 for the heating medium is made with one end of this cross passageway. This structure is especially designed for hot 35 water radiators. The advantage of the intermediate supply connection and passageways is that the hot water, having a chance to cross through the series of sections at an intermediate height, will heat the cool 40 water with which the radiator is filled more rapidly than when the supply connection is made at the bottom, and the radiator will therefore get hot in much less time than usual. The intermediate cross passageway 45 will be the same as the top and bottom cross passageways, standard practice being followed. The bottom cross passageway also has a connection with the supply-connection 8, to permit water to drain back into the 50 latter when the radiator is to be emptied.

I claim:

A radiator comprising a series of vertical sections assembled side by side, and having an intermediate and a bottom cross 55 passageway, a supply connection to the intermediate cross passageway, and a drain connection between the bottom cross pas- sageway and the supply connection.

In testimony whereof I affix my signature. 60

PHILIP SCHNEIDER.
